(57) **CLAIM**

I claim the ornamental design of a connector for vehicle hairpin radius rods, as shown and described.

DESCRIPTION

FIG. 1 is a perspective view of a connector for vehicle hairpin radius rods.

FIG. 2 is a rear elevation view of the connector for vehicle hairpin radius rods.

FIG. 3 is a front elevation view of the connector for vehicle hairpin radius rods.

FIG. 4 is a left side elevation view of the connector for vehicle hairpin radius rods.

FIG. 5 is a right side elevation view of the connector for vehicle hairpin radius rods.

FIG. 6 is a top plan view of the connector for vehicle hairpin radius rods.

FIG. 7 is a bottom plan view of the connector for vehicle hairpin radius rods; and,

FIG. 8 is a top plan view of the connector for vehicle hairpin radius rods.

The broken lines rendered in FIG. 3 of the drawings illustrate portions of the connector for vehicle hairpin radius rods and form no part of the claimed design. The broken line showing of the vehicle hairpin radius rod in FIG. 8 illustrates the environment of the claimed design and forms no part thereof.

1 Claim, 8 Drawing Sheets
